(57) CLAIM

I claim the ornamental design for the garage floor covering having the appearance of a highway, as shown and described.

DESCRIPTION

FIG. 1 is a perspective view of the garage floor covering having the appearance of a highway,

FIG. 2 is a top view thereof,

FIG. 3 is a bottom view thereof,

FIG. 4 is a front side view thereof,

FIG. 5 is a back side view thereof,

FIG. 6 is a left side view thereof,

FIG. 7 is a right side view thereof; and,

FIG. 8 is a environmental perspective view, showing a car in dashed lines parked atop the invention. The car in dashed lines forms no part of the invention.
